(57) **CLAIM**

The ornamental design for a hunter casket, as shown and described.

DESCRIPTION

FIG. 1 is a front elevational view of the casket illustrating my new design.

FIG. 2 is a rear elevational view.

FIG. 3 is a left side elevational view.

FIG. 4 is a right side elevational view.

FIG. 5 is a top view; and,

FIG. 6 is a bottom view.

The broken lines form no part of the claimed design.
